CARTON

Clarence W. Vogt, New York, N. Y., assignor, by
mesne assignments, to Owens-Illinois Glass
Company, Toledo, Ohio, a corporation of Ohio

Application April 29, 1936, Serial No. 76,898

6 Claims. (Cl. 229—39)

The present invention relates to cartons of that type in which the closure is formed by foldable and interlockable flaps.

One object is to provide a carton having a new and improved form of closure flaps which may be interlocked by merely pressing into and slightly beyond final closure position.

Another object is to provide closure flaps which when interlocked will effectively withstand diagonal compressive forces incident to ordinary handling, and which will prevent collapse of the carton and snapping of said flaps outwardly into open position.

A further object is to provide a carton having new and interlockable closure flaps adapted to effectively withstand internal pressure such as that due to the weight of the material in said carton, tending to bulge said flaps outwardly into open position.

20 The important features of the invention will be apparent from the following description of one embodiment and from an inspection of the accompanying drawing in which:

Figs. 1-5 are perspective views of the lower end 25 of a carton shown in inverted position, and showing respectively the bottom closure flaps in successive phases of being folded into interlocked position.

Fig. 6 is a section through the lower end of a 30 carton after the closure flaps have been interlocked, and the carton turned into its normal upright position and filled, and

Fig. 7 is a plan view of the bottom portion of the blank from which the carton shown in Figs. 35 1-6 is constructed.

The carton in the specific form illustrated is 40 constructed from a blank made of comparatively rigid material such as cardboard, and having a series of longitudinally extending score or crease lines 11 along which the blank is folded to form the side walls 12 of the carton. One side of the blank may be provided with the usual comparatively narrow side flap adapted to be adhesively secured to the opposite side of the blank to form 45 a tubular carton of rectangular cross-section.

The blank is provided at one end with a pair of extensions 14 and 15 forming the inner opposed closure flaps and a pair of extensions 16 and 17 forming the outer opposed closure flaps, 50 these extensions being foldable in the usual manner along the crease or score lines 18 extending transversely of the blank.

The two inner flaps 14 and 15 are preferably 55 rectangular in shape and preferably of such length that the end edges thereof will come close

together or directly abut when these flaps have been folded inwardly across the end of the carton as shown in Fig. 2. To permit these inner flaps 14 and 15 to be interlaced with the outer flaps, they are each provided with a crosswise 5 slit or incision 20 extending substantially parallel to the score line 18, and a second slit 21 extending substantially at right angles to the slit 20 and forming therewith a flap section 22. This flap section 22 may be deflected out of the plane 10 of the main body of the inner flap to form a gap along the slit 20 sufficiently wide to permit the easy insertion therethrough of a side portion of the outer flap 16. The angular slits 21 and 22 on the two inner flaps 14 and 15 are so arranged 15 that when said flaps are folded inwardly across the open end of the carton, two slits 21 will be in alignment and the two flap sections 22 will be in symmetrical relationship as shown in Fig. 2.

The outer flap 16 has its side edges converging 20 from the score line 18 along diagonal lines to form a base portion 26 of a length substantially equal to the distance between the slit 21 and the adjacent edge of the flap 14 or 15 and beyond this base portion there is a tongue 25. The base 25 portion and the terminal portion of the tongue have widths equal to or slightly less than the distance between the two slits 20 when the inner flaps are in closure position.

On opposite edges of the tongue 25 there are 30 provided a pair of opposed side extensions in the form of tabs 27 adapted to be inserted respectively in the slits 20, there being a pair of opposed notches 28 at the sides of the tongue beyond said side tabs 27 to form the end of the 35 tongue as an end tab 30.

The outer flap 17 is provided with a base portion 32 tapered towards its outer end similar to the base portion 26, and beyond this base portion there is a tongue 33 having a maximum 40 width substantially the same as the width of the tongue 25, that is slightly less than the distance between the slits 20 of the two inner flaps when said flaps are folded inwardly in closure position. The flap 17 differs from the flap 16 primarily in that it does not have any side tabs.

In order to interlock the flaps of the carton, they must be deflected inwardly of the carton. This folding and interlocking operation is difficult unless the carton is empty or there is room 50 for this inward deflection of the flaps. For that reason my improved closure flaps are shown applied to the bottom of the carton. However, as far as certain aspects of the invention are concerned, similar closure members may be pro- 55

vided at the upper end of the carton if said carton is not intended to be filled to the top.

With the opposite sides of the blank adhesively secured together to form a tubular body open at both ends, it is held as shown in Figs. 1-5 so that the flaps are readily accessible. In Fig. 1 the flaps are shown in open position ready to be folded and interlocked. The folding and interlocking of these flaps is started by folding inwardly the two flaps 14 and 15 across the open end of the carton, as shown in Fig. 2. The flap 17 is then folded over the inner flaps 14 and 15 and pressed downwardly as shown in Fig. 3 so that the two inner flaps 14 and 15 are deflected towards the interior of the carton and the flap sections 22 are deflected inwardly with respect to the main body of said inner flaps to form a gap along the slits 20. By providing the flap 17 with a tapered base portion 32, the oblique side edges of this base portion will serve more effectively to bend the two inner flaps 14 and 15 downwardly in the interior of the carton as shown in Fig. 3.

While the flap 17 is held against the two inner flaps 14 and 15 by a finger as shown in Fig. 3, the other outer closure flap 16 is pressed downwardly until the side tabs 27 reach the slits 20. By further pressure the tabs will snap through gaps formed along the slits 20 as shown in Fig. 4. By providing the outer flap 16 with a tapered base portion, the inward folding of this flap is facilitated.

Since the two inner flaps 14 and 15 are held downwardly by the outer closure flap 17, the inward folding of the other closure flap 16 in the position shown in Fig. 4 will not subject the side tabs 27 to any excessive bending stresses tending to crease said side tabs.

After the side tabs 27 of the outer flap 16 have been snapped through the slits 20, the finger pressure on the two flaps 16 and 17 is released to permit all of the flaps to rise into the position shown in Fig. 5. In this position, the end tab 30 will extend slightly above the plane of the two inner flaps 14 and 15 so that any diagonal compression on the carton incident to ordinary handling will cause either one or the other side edge of said end tab, as well as the side edges of the tongues 33, to abut the inwardly facing edge of its corresponding slit 20, thereby effectively preventing the flaps from snapping outwardly into open position, and preventing diagonal collapsing of the carton.

The outer closure flap 17 serves not only to deflect the two inner flaps 14 and 15 inwardly during the folding and interlocking operation, but also serves to deflect the end tab 30 outwardly beyond the plane of the inner flaps 14 and 15, due to the inherent tendency of said flap 17 to bend outwardly along its crease line 18.

In Fig. 6 is shown the carton after its bottom flaps have been interlocked, the carton turned into its upright position, and the interior thereof filled. This carton is adapted to be filled with any suitable material and is shown in conjunction with an inner expandable bag 35 made of thin flexible material and containing a suitable liquid. This bag may be permanently secured to the carton or may be detachable therefrom. The pressure of the filled bag 35 against the bottom closure flaps serves to bulge these flaps slightly outwardly when the carton is lifted from a supporting surface, as shown in Fig. 6. This bulging serves to more effectively deflect the end tab 30 outwardly beyond the plane of the inner

flaps 14 and 15, so that the use of the side edges of this end tab for effectively withstanding diagonal compression on the carton, is assured.

At the central portions of the bottom flaps, where the greatest bulging of the carton takes place, there are three overlapping flap sections which, due to the frictional contact therebetween, will effectively prevent the flaps from bulging outwardly to any extent sufficient to snap the flaps into open position. These three overlapping sections are the flap sections 22, the tongue 33 and the tongue 25. Furthermore, the internal pressure of the filled carton against the flap section 22 serves to close the slits 20 and to effectively hold the side tabs 27 therein.

The end tab 30 is shown with parallel sides, but may be flared inwardly towards its base to form side ears adapted to overlap the slits 20.

Having thus described my invention, what I claim as new and desire to secure by Letters Patent is:

1. A carton having four flaps at one end, two of which are adapted to form the inner opposed closure flaps and the other two the outer opposed closure flaps, said inner flaps each having an L-shaped slit with one portion disposed substantially parallel to the base of the flap and another portion extending to the end of the flap, one of said outer flaps having side tabs adapted to be inserted through said slits to interlock said latter flap and said inner flaps when in carton closure position, the other outer flap being provided with a tongue at its outer end having a maximum width substantially equal to the distance between said slits when said inner flaps are in said carton closure position.

2. A carton having four foldable extensions at one end, two of said extensions being adapted to form the opposed inner closure flaps and the other two the opposed outer closure flaps, each of said inner flap extensions being provided with an edge extending substantially parallel to its fold line and spaced inwardly from the outer end of said inner flap, one of said outer flap extensions having side tabs adapted to extend along the inner surfaces of said inner flaps, and outwardly beyond said edges, the outer end of said last mentioned outer flap having a tab the width of which is not materially less than the distance between said edges, the sides of said end tab being adapted to abut said edges when all of said flaps are in carton closure position.

3. A carton having at one end a pair of opposed inner closure flaps and a pair of opposed outer closure flaps, each of said inner flaps being provided with an edge extending substantially parallel to its fold line and spaced inwardly from its outer end, one of said outer flap having a tongue including a pair of side tabs and an end tab extending outwardly beyond said side tabs, said side tabs being adapted to extend on the inner sides of the inner flaps beyond said edges, and the sides of said end tab being adapted to abut said edges to withstand the diagonal compression on said carton when all of said flaps are in closure position.

4. A carton having at one end a pair of opposed inner closure flaps and a pair of opposed outer closure flaps, each of said inner closure flaps being provided with a crosswise slit extending substantially parallel to the fold line of said latter flap, and another slit extending substantially at right angles to said first mentioned slit, said angular slits defining a flap section adapted to be deflected out of the plane of the

- main body of said latter inner flap, one of said outer flaps having a tongue at its outer end formed with a pair of side tabs, and an end tab extending beyond said side tabs, the other closure flap being provided with a tongue at its outer end having a maximum width substantially equal to the distance between the crosswise slits of said inner flaps when in closure position, said latter tongue being adapted to overlap the outer surfaces of said flap sections, and the other first mentioned tongue being adapted to overlap the outer surface of the second mentioned tongue, with the side tabs of said first mentioned tongue extending through said crosswise slits and along the inner surfaces of said inner flaps. 5
- 10 5. A carton having at one end a pair of opposed inner closure flaps and a pair of opposed outer closure flaps, each of said inner closure flaps being provided with a crosswise slit extending substantially parallel to the fold line of said latter flap, one of said outer flaps having a tongue at its outer end formed with a pair of side tabs, and an end tab extending beyond said side tabs, 15 the other closure flap being provided with a tongue at its outer end having a maximum width substantially equal to the distance between the crosswise slits of said inner flaps when in closure position, said latter tongue being adapted to overlap the outer surfaces of said inner flaps, and the other first mentioned tongue being adapted 20 to overlap the outer surface of the second mentioned tongue, with the side tabs of said first mentioned tongue extending through said crosswise slits and along the inner surfaces of said inner flaps. 25
